(Cl. D19—2)

FIG. 2

FIG. 1

FIG. 3

FIG. 4

FIG. 6

FIG. 5

FIG. 8

FIG. 7

FIG. 1 is a perspective view of a casket hardware member, showing my new design wherein the member is angled to fit the corners of a casket;

FIG. 2 is a top plan view of the casket hardware member shown in FIG. 1;

FIG. 3 is an end elevational view of the casket hardware member shown in FIGS. 1, 2 and 3, the opposite end being substantially a mirror image thereof;

FIG. 4 is a bottom plan view of the casket hardware member shown in FIGS. 1, 2 and 3;

FIG. 5 is a perspective view of the casket hardware member of my design somewhat reduced in size and adapted to fit on the flat sides of the casket as a handle bracket;

FIG. 6 is a top plan view of the casket hardware member shown in FIG. 5;

FIG. 7 is a bottom plan view of the casket hardware member shown in FIGS. 5 and 6; and

FIG. 8 is an end view of the casket member shown in FIGS. 5, 6 and 7, the opposite end being a substantially mirror image thereof.

The broken line fragmentary showing of a casket in FIG. 1 is for illustrative purposes only and the broken line fragmentary showing of a handle in FIG. 5 is for illustrative purposes only.

This application is a continuation of my co-pending application Serial No. 63,420, filed January 3, 1961, and also of my co-pending application Serial No. 63,421, filed January 3, 1961.

I claim:

The ornamental design for a casket hardware member, substantially as shown and described.
